CLAIM

The ornamental design for a cap for pharmaceutical mixing container, as shown and described.

DESCRIPTION

FIG. 1 is a perspective view of a cap for pharmaceutical mixing container, showing our new design;

FIG. 2 is a perspective cross-sectional view taken along line 2-2 in FIG. 4;

FIG. 3 is a front view thereof;

FIG. 4 is a top plan view thereof;

FIG. 5 is a bottom plan view thereof; and,

FIG. 6 is a right side view thereof.

The rear and left side views are omitted, because they are mirror images of the front and right side views, respectively.
